UNITED STATES PATENT OFFICE.

ARTHUR R. BAKER, OF INDIANAPOLIS, INDIANA, ASSIGNEE TO IRA T. SWARTZ, OF INDIANAPOLIS, INDIANA.

OIL BURNER.

Application filed January 14, 1925, Serial No. 2,387. Renewed June 7, 1928.

My said invention consists in an improved construction of oil burner, the purpose being to provide an apparatus for burning any character of fuel oil in atomized condition and to provide an apparatus in which such fuel will be practically all consumed, or perfect consumption attained, thereby to achieve economy in the use of fuel and freedom from smoke, all as will be herein-
10 after more fully described and claimed.

Referring to the accompanying drawings, which are made a part hereof and on which similar reference characters represent similar parts.

15 Figure 1 is a horizontal section through a furnace equipped with my said oil burning apparatus, several parts of which are shown in elevation,

Figure 2, a vertical section through said furnace showing the oil burner in side elevation,

20 Figure 3, a detail view showing the retort or burner within the furnace on an enlarged scale and illustrating its construction more
25 in detail,

Figure 4, a detail view of the discharge nozzle of the oil burner, and

Figure 5, such a view showing a modified form of nozzle.

30 In said drawing the portions marked A represent the exterior wall of the furnace, B the fire pot, C the retort, and D the oil burner nozzle. The furnace A may be of the form shown or of any approved construction and
35 arrangement, the fire pot B being provided with an opening 10 leading to the outside.

The burner or retort C, as shown, is composed of a cylindrical casing 11 and bottom 12 and a series of superimposed disks 13
40 each formed with a central downwardly depending boss 14 and with a downwardly depending flange 15 at its periphery. A radial partition 16 is positioned at one side of the chamber said partition extending from
45 the bosses 14 to the flanges 16 dividing the chambers formed between the disks. On one side of said partition is an inlet 17 through which the flame from the burner is discharged into said passages between the
50 disks and on the opposite side of said partition is an outlet 18 through which the burnt gases escape to the chamber above the upper disk and out through an aperture 19 of the retort. It should be noted that the
55 uppermost plate extends over the inlet to

the partition but has a segment omitted above the outlet space for upward escape of products of combustion. The cylinder 11 and disks 13 are preferably formed of carbonfrax or of electrically sintered alundum, 60 both of which materials have been used and found satisfactory being of high refractory resisting power and also having great heat conductive properties. Surrounding the cylinder 11 is a cylindrical covering 20 of 65 transparent material, preferably mica, which has been used and found satisfactory for a purpose which will be presently described.

It will be understood, of course, that the substances mentioned herein, of which the 70 central parts are constructed, are substances which have been found suitable for the purpose, but that I do not intend to limit myself to such substances, but to have it understood that any substance found suitable for 75 any part of the apparatus may be substituted without departing from my invention. It is also to be understood that the parts 13 need not be shaped as circular disks nor need they be located in horizontal planes, 80 but their form, position and relation to each other may vary between wide limits.

The oil burner nozzle D is connected with a blower 21 which is adapted to be operated by a motor 22 driven by electric power 85 through a circuit composed of wires 23 and 24 controlled by a switch 25 conventionally shown in Figure 1.

The fuel oil may be contained in a suitable tank or container 26 positioned so that 90 the oil will flow to the intake side of a carbureter 27 which is connected to the fan or blower casing 21. Said carbureter need not be particularly described herein as any carbureter found suitable may be employed. 95 I prefer, however, the carbureter forming the subject-matter of application No. 752-253, filed November 25, 1924, which has been employed in this apparatus and found to be particularly advantageous inasmuch 100 as it maintains a low vacuum at high speed of the blower.

A tube or coil 28 is mounted to extend into the furnace, as best shown in Figure 1, one end being open to the outer air and the other to the intake side of the carbureter to supply pre-heated air for mixture with the oil.

In operation the blower is driven to create the suction through the carbureter which 110

operates to draw in the fuel oil from the supply tank and also the air through coil 28 and mix, atomize and drive the mixture in atomized form through the nozzle D into the 5 retort or burner within the cylinder C.

In operation a certain portion of the oil will remain in liquid form and pass along the lower side of the nozzle. It is desirable that all the oil shall be thoroughly atomized 10 and mixed with air in order that perfect consumption may be attained. For this purpose I attach a supplemental nozzle or air tube 30 to the top side of the nozzle D and bring it to a point adjacent the under 15 side of the discharge opening in nozzle D so that air discharged from said tube will form a blast in an angular direction across the direction of the blast from the main tube, the end of the tube 30 being curved 20 upwardly, as best shown in Figure 4, for this purpose. By this means such liquid fuel as may be at the lower side of the nozzle D will be drawn outwardly by the suction and thoroughly atomized and mingled 25 with the remainder of the atomized fuel and discharged therewith into the retort or burner C. The fuel being ignited at the mouth of the discharge nozzle the flame caused by the burning fuel will be 30 impelled through the opening 17 in one side of the burner and through the pass-ways or chambers between the disks 13 entirely around the burner from one side to the other to burn the gases escaping through 35 the opening 18 and out through the furnace and the stack.

In operation the heat caused by the flames will raise the temperature of the burner or retort until the cylinder C becomes a bright 40 red which reflects through the translucent cover 20 and is absorbed by the walls of the heating chamber B and radiates through said walls into the heating chamber of the furnace. The fuel is discharged in atomized 45 form from the nozzle between the hot plates. The minute drops or atoms strike the hot plates and are vaporized and ignited. As they are completely surrounded by flame, the free carbon will be utterly consumed, 50 and all the fuel will be so changed or consumed that no visible smoke results from the combustion.

The translucent cylinder or cover 20 is an 55 important feature of the construction of the retort or burner inasmuch as without such a cover the cylinder C will not maintain the high red color and cause the heat raised to be reflected against the walls of the heating chamber.

60 In Figure 5, I have shown a modified construction of a nozzle wherein a spiral partition 31 is mounted within the nozzle D and is adapted to direct a part of the current of air passing through said nozzle adjacent to the mouth thereof from the upper

65 to the lower side so that, as in the case of the tube 30, the dry air from the top of the nozzle is utilized to mingle with and atomize the liquid fuel in the bottom of the nozzle. Such a modified form may be substituted for the tube 30 if preferred, as will 70 be readily understood.

Having thus fully described my said invention, what I claim as new and desire 75 to secure by Letters Patent is:

1. An oil burner comprising a nozzle, means for directing an air blast through said nozzle, a carbureter connected with said means, means for supplying fuel oil and air to the carbureter, and an air conduit adapted to take air from the upper part of the nozzle and discharge it in the form of an upward blast at the lower side of its discharge end, substantially as set forth. 80

2. An oil burner comprising a nozzle, means for directing an air blast through said nozzle, fuel supplying means, air supplying means, a carbureter connected with said fuel and air supplying means at its intake side and with the means for creating the air blast at its discharge side, and an air conduit connected with the nozzle to take air from its upper side at a point back from its discharge end and discharge it in the form of a forward blast at the lower side of its discharge end, substantially as set forth. 90

3. In an oil burning apparatus, means for supplying fuel oil in atomized form 100 including a nozzle, a burner comprising imperforate plates spaced apart and adapted to receive the fuel from the nozzle laterally between them, a wall of refractory material surrounding said plates, and an outer covering of translucent material about said wall, substantially as set forth. 105

4. A burner comprising a casing, superposed disks in said casing each having a central downwardly depending boss and a peripheral downwardly depending flange, a partition disposed radially between said bosses and flanges and forming a tortuous passage from one side of said partition around to the other side thereof one side of said partition providing an inlet for the burner and the other side of said partition having communication with the casing forming an outlet for the burner, substantially as set forth. 110

5. In an oil burner, a chamber having end pieces of refractory material, an outer wall of refractory material enclosing the space between said end pieces, inlet and outlet ports in said outer wall, and partitions dividing the chamber into a plurality of substantially parallel passages of subsidiary chambers each leading from the inlet port to the outlet port, substantially as 115 set forth. 120

6. In an oil burner, a cylindrical outer wall having a segmental opening, a longitudinal partition bisecting said opening, end closures one of which is cut away opposite said segmental opening at one side only of said partition, and means for feeding atomized fuel into the other opening, substantially as set forth.
7. In an oil burner, a cylindrical outer wall having a segmental opening, a longitudinal partition bisecting said opening, end closures one of which is cut away opposite said segmental opening at one side only of said partition, plates intersecting the axis of the chamber within said wall to provide passages leading from the inlet port to the outlet port, and means for feeding atomized fuel into the other opening, substantially as set forth.
8. In an oil burning apparatus, a burner comprising a casing having inlet and outlet ports and spaced horizontal partitions in the casing arranged to simultaneously conduct the flame in a circular path through the burner, and means for discharging atomized fuel into the chamber through said inlet port, substantially as set forth. ²⁵
9. In an oil burning apparatus, a burner comprising a plurality of partitions, a spacing element intermediate each pair of partitions, said spacing elements being similarly arranged and disposed in abutting relation to form an obstruction, a radial partition separating the inlet from the outlet ports, and means for supplying atomized fuel laterally between said partitions at one side of said radial partition whereby the fuel will pass in a circuitous path around the same, substantially as set forth. ³⁰
10. In witness whereof, I have hereunto set my hand and seal at Indianapolis, Indiana, this 8th day of January, A. D. nineteen hundred and twenty-five. ³⁵
- ARTHUR R. BAKER. [L. S.]
